CLAIM

The ornamental design for a motorized vehicle, as shown and described.

DESCRIPTION

FIG. 1 is a front, right side and top perspective view of a motorized vehicle showing our new design;

FIG. 2 is a front perspective view thereof;

FIG. 3 is a rear perspective view thereof;

FIG. 4 is a right side perspective view thereof;

FIG. 5 is a left side perspective view thereof;

FIG. 6 is a top perspective view thereof; and,

FIG. 7 is a bottom perspective view thereof.

The broken lines in the drawings illustrate portions of the motorized vehicle that form no part of the claimed design.
